UNITED STATES PATENT OFFICE.

FREDERICK W. BEARDSLEE, OF SAN FRANCISCO, CALIFORNIA, ASSIGNOR TO MARY TAYLOR BEARDSLEE, OF SAN FRANCISCO, CALIFORNIA.

SEPARATING AND DEWATERING DEVICE.

1,262,738.

Specification of Letters Patent. Patented Apr. 16, 1918.

Application filed September 25, 1916. Serial No. 121,990.

To all whom it may concern:

Be it known that I, FREDERICK W. BEARDSLEE, a citizen of the United States, residing at the city and county of San Francisco and 5 State of California, have invented new and useful Improvements in Separating and Dewatering Devices, of which the following is a specification.

This invention relates to a separating and 10 dewatering device for use in any association where it is desired to separate solids from liquids, or light from heavy particles, or to thicken or clarify any substance in solution.

The present device has been used with 15 marked success in mining regions where water is scarce, for the purpose of removing the water from the pulp or slime, and clarifying it for re-use. The operation of the device is continuous and automatic, and 20 capable of adjustment to vary the consistency of the separated substances. The principle of operation of the device may be likened to that of an impulse turbine, the inflowing material being directed upon the turbine wheel to operate the same, whereby a 25 gentle vortical motion is imparted to the contents of the container for the purpose of moving the heavier substances outward. The lighter substances or clarified water 30 can then be drawn off from the inner portion of the container. In connection with the turbine wheel I provide float means for regulating the discharge of the heavier substances in accordance with the height of the 35 material in the container.

The construction of the device is simple and economical and the cost of its maintenance and operation is practically nothing inasmuch as no external power is necessary 40 to operate the device, and no attention is required after the parts are once adjusted and put into operation.

One form which my invention may assume is exemplified in the following description, and illustrated in the accompanying drawing, in which:—

Figure 1 shows a vertical central sectional view of the complete device.

Fig. 2 shows a plan view of the same.

Fig. 3 shows a horizontal sectional view 50 on the line 3—3 of Fig. 1.

In the present device I employ an inverted conical tank 10 carried on a base 11 and fitted with a vertical stem 12 extending 55 along its longitudinal axis, which stem car-

ries at its lower end a conical valve 13 working in a beveled seat 14 fitted in the lower end of the tank. The upper end of the stem is fitted slidably and rotatably in a bearing 15 formed on radial arms 16 resting removably upon the top of the tank. The said stem 12 is surrounded by an inclosed casing 17 spaced therefrom and secured at its lower end to the valve 13 and carries on its upper end an enlarged hollow head 18 secured to the stem 12, and forming a float. On the periphery of the head at suitable intervals, I arrange buckets 19 which, supported on downwardly extending arms 20 fixed to the head and inclined outwardly at 60 its lower end. The casing 17 is provided on its exterior surface with blades 21 curved in the same direction as the buckets 19. Spaced from the blades 21 is a series of baffles or gates 22 each supported on arms 23 fixed to the tank, said gates being overlapped 65 slightly at their adjacent ends and arranged shingle fashion although spaced apart to allow movement of the water or material between.

An inlet pipe or chute 24 is arranged at the top of the tank with a discharge end directed into the path of the buckets 19. An outlet pipe 25 is arranged at one side of the tank and has its mouth positioned between 70 the blades 21 and baffles 22, for drawing off the liquid or lighter substance. A valve 26 is provided for the pipe 25 for regulating the discharge of water.

In the operation of the device the material 75 to be dewatered, separated, or otherwise treated, is introduced through the pipe or chute 24 with sufficient velocity to cause a slow rotatable movement of the float and valve mechanism through the impulse of the 80 material against the buckets 19. Normally the tank will be filled with material to a point where the float raises and opens the valve 13. By means of the blades 21 the body of the contained material in the tank will be 85 given a swirling or vortical motion in the direction shown by the arrows in Fig. 3. The result of this is that the heavier particles contained in the material will be 90 moved outwardly between the gates 22, leaving the clear water or lighter substances nearer the center of the tank where they will pass off through the outlet pipe 25. The 95 heavier particles or solid substances moving outwardly will be directed downwardly and 100 105 110

inwardly by the converging sides of the tank 10 and upon reaching the bottom of the tank will pass out through the valve 13.

The float valve automatically maintains the proper relation of the separated elements. If the valve should open so far as to permit light particles or liquid to escape with the solids, then the volume of material in the tank will decrease on account of the 10 regulated and even inflow of the same. Thereupon the float will be lowered and the valve closed to check the excessive discharge of the materials. On the other hand if the valve does not open sufficiently to allow the 15 solids to escape, the height of the material in the tank will rise, lifting the float and further opening the valve. The handling of any volume of material can be provided for, and the exact consistency of the material discharged through the bottom valve 20 can be regulated by adjusting the valve 25 through which the clear liquid is discharged. For instance if the solution introduced into this device contains 20% of 25 solids, then 80% must be liquid. If the valve in the clear liquid discharge pipe be opened so as to let out one half of the incoming clear liquid, in other words 40% of water, the 40% of water remaining must 30 mix with the 20% of solids and be discharged through the valve at the bottom of the cone, and the material so discharged at the bottom will contain 33.3% of solids. Therefore, any desired consistency of such 35 discharged material can be secured by the simple opening or closing of the clear liquid valve. The float has a screw cap 27 to permit the introduction of ballast whereby to insure the closing of the valve 13 when a 40 pre-determined level of the material in the tank is reached. After being once adjusted, the buoyancy need not be varied.

All of the material, both liquids and solids, is deposited in the cone outside of 45 the baffle sheets 22, and the swirl of the water, by reason of the rotation of the valve stem, will prevent the heavier particles from floating into the center from which the clear liquid is drawn off.

This device is ideally adapted for use with suction dredges for the construction of levees, as by the use of the same the levee material can be deposited on the land in the exact consistency required and the excess 55 water pumped by the dredge, returned by gravity to the stream.

While I have shown herein and described but one form of my invention, it will be understood nevertheless that the same is susceptible of modification, and that various changes in the construction and arrangement of the several parts may be employed without departing from the spirit of the invention as disclosed in the appended 60 claims.

Having thus described my invention, what I claim and desire to secure by Letters Patent is—

1. In a separating device, a container, centrifugal means therein automatically operated by the gravity inflow of material at the top thereof for separating the lighter from the heavier substances, and means for varying the consistency of the heavier substances discharged by varying the volume 75 of light substances discharged.

2. In a separating device, a container, rotary means operated by the gravity inflow of material at the top of the container for imparting a gentle vortical motion to the 80 contents of the container whereby to move the heavier substances outwardly, allowing the lighter substances to remain near the center of the container, means for drawing off the lighter substances from the inner 85 and upper portion of the container, and means for drawing off the heavier particles from the lower portion thereof.

3. In a separating device, a container, rotary means operated by the gravity inflow 90 of material at the top of the container for imparting a gentle whirling motion to the contents of the container whereby to move the heavier substances outwardly, allowing the lighter substances to remain near the 95 center, means for drawing off the lighter substances from the inner and upper portion of the container, means for discharging the heavier substances from the bottom thereof, and means for automatically regulating the discharge of the latter in accordance with the height of the material in the 100 container.

4. In a separating device, a container, a turbine wheel therein, means for admitting 105 material under gravity pressure to said container and directing it against the buckets of said wheel to rotate the latter and impart a gentle outward movement to the contents of the container whereby the heavy 110 particles or solid substances are moved outwardly and the lighter particles and liquid substances remain near the center of the container, baffles dividing the container into inner and outer zones, and means for continuously drawing off the separated substances from each of the zones.

5. In a separating device, a container, a turbine wheel therein, means for admitting the material to said container under gravity 120 pressure and directing it against the buckets of said wheel to rotate the latter and impart a gentle outward movement to the contents of the container whereby the heavy particles or solid substances are moved outwardly for settlement and the lighter particles and liquid substances remain near the center of the container, means for drawing off the light material from the inner and upper portion of the container, means for 125 130

drawing off the heavy material from the bottom of the container, and float means carried by the turbine wheel for regulating the size of the discharge vent in the bottom 5 of said container.

6. In a separating device, an inverted conical tank, means operated by the inflow of material under gravity pressure thereto for imparting a gentle vortical motion to 10 the contents of the tank whereby to move the heavy particles and solid substances outwardly, for settlement to the bottom of the tank, valve-controlled means for drawing off the light particles and liquid substances 15 from the upper and inner portion of the tank, means for drawing off the heavy particles and solid substances from the bottom of the tank, a valve for controlling said last-named means, and a float for regulating the valve 20 in accordance with the height of the material in the tank.

7. In a separating device, an inverted conical tank having a discharge orifice at its bottom, a conical valve seated in said 25 discharge orifice for controlling the same, a floating turbine wheel in said tank journaled upon a vertical axis, said valve forming the lower pintle for the wheel, means for admitting material into said tank under 30 gravity pressure and directing it against the buckets of the wheel to rotate the latter and impart a gentle whirling motion to the contents of the tank whereby to move the heavy particles and solid substances outwardly for settlement to the bottom of the tank, means for drawing off the light particles and liquid substances from the upper and inner portion of the tank, said bottom 35 discharge orifice permitting the heavy particles and solid substances to escape in quantities varying in accordance with the height 40 of the material in the tanks.

8. In a separating device comprising a tank with sloping sides to a central discharge at the bottom, a float valve for said 45 discharge, the float mounted for rotation while in suspension in the tank, and having peripheral buckets, a pulp nozzle by which the entering pulp is directed against the 50 blades to rotate the latter and said float.

9. In a separating device comprising a tank with sloping sides to a central discharge at the bottom, a float valve for said discharge, the float mounted for rotation 55 while in suspension in the tank, and having peripheral buckets, a pulp nozzle by which the entering pulp is directed against the blades to rotate the latter and said float, and submerged blades carried by the float 60 arranged to direct the solids outwardly toward the sloping sides of the tank.

10. In a separating device comprising a tank with sloping sides to a central discharge at the bottom, a float valve for said 65 discharge, the float mounted for rotation

while in suspension in the tank, and having peripheral buckets, a pulp nozzle by which the entering pulp is directed against the blades to rotate the latter and said float, submerged blades carried by the float arranged 70 to direct the solids outwardly toward the sloping sides of the tank, and spaced submerged baffles arranged between the sides of the tank and the blades, between which baffles the currents created by the blades circulate. 75

11. In a separating device comprising a tank with sloping sides, to a central discharge at the bottom, a float mounted for rotation 80 while in suspension in the tank, and having peripheral buckets, a pulp nozzle by which the entering pulp is directed against the blades to rotate the latter and said float, submerged blades carried by the float arranged 85 to direct the solids outwardly toward the sloping sides of the tank, and spaced submerged baffles arranged between the sides of the tank and the blades, between which baffles the currents created by the 90 blades circulate, and means for drawing off the clear liquid from the zone between the blades and baffles.

12. In a separating device, a container, rotary means for separating the lighter 95 from the heavier substances, a valve controlled discharge pipe for drawing off the lighter substances from the upper and inner portion of the container, a valve controlled discharge orifice at the bottom of the container for drawing off the heavier substances, and a float carried by said rotary means for controlling the valve of the said last-mentioned discharge orifice, whereby, by varying the volume of the light substances drawn off, the consistency of the heavier substances discharged can be positively regulated. 100

13. A separating device comprising a tank having a discharge orifice in its bottom, and 110 means for supplying material in solution thereto at the top, a valve for controlling said discharge orifice, a float for regulating said valve in accordance with the height of the material in the tank, means operated 115 by the inflow of the material in the tank whereby to impart a swirling motion to such material, and cause the heavy particles therein to be moved outwardly allowing the lighter particles to remain near the center, 120 and discharge means communicating with the inner portion of the tank and having a regulable means for varying the volume of material drawn off and consequently the consistency of the material discharged at 125 the bottom of the tank.

14. A separating device comprising a tank having a discharge orifice at its bottom, and means for supplying material in solution thereto at the top, a valve for controlling 130

- said discharge orifice, a float for regulating said valve in accordance with the height of the material in the tank, rotatable means operated by the inflow of material for imparting a swirling motion to the material in the tank whereby to move the heavier particles outwardly, baffle plates outside of which the material is introduced and surrounding said rotatable means whereby to prevent entrance of the heavier particles to the inner portion of the tank, and a discharge pipe communicating with said tank inside of said baffle plates and provided with regulable means to vary the volume of liquid discharged therethrough, and consequently the consistency of the material discharged through the bottom orifice.
15. A separating device comprising an inverted conical tank having a discharge opening at its bottom, and means at its top for supplying the material thereto in solution, a valve for controlling said discharge opening, a vertical stem for said valve journaled for rotation in the tank, a float carried by the upper end of said valve stem for regulating the valve in accordance with

the height of the material in the tank, buckets on said float in the path of the incoming material for rotating said valve stem, vanes carried by said valve stem below the float for imparting a swirling motion to the material in the tank whereby to move the heavier particles outwardly, baffle plates carried on the tank and surrounding said vanes to prevent return movement of the heavier particles to the inner portion of the tank, and a discharge pipe located between the baffle plates and the rotatable vanes for drawing off the clarified substances, and regulable means for said discharge pipe whereby to vary the volume of liquid drawn off and consequently the consistency of the material discharged through the bottom opening in the tank.

In testimony whereof I have hereunto set my hand in the presence of two subscribing witnesses.

FREDERICK W. BEARDSLEE.
